(57) CLAIM

The ornamental design for a piano mat, as shown and described.

DESCRIPTION

FIG. 1 is a front perspective view of a piano mat, showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of a portion indicated in FIG. 1;

FIG. 10 is an enlarged view of a portion indicated in FIG. 1;

FIG. 11 is an enlarged view of a portion indicated in FIG. 1; and,

FIG. 12 is an enlarged view of a portion indicated in FIG. 2. The broken lines in the figures illustrate portions of the piano mat that form no part of the claimed design.
